HEMODIALYSIS FLUID CONDITIONING AND MONITORING APPARATUS

Anthony J. Carsello, Rolling Hills, Calif., assignor to Western Gear Corporation, Lynwood, Calif., a corporation of Washington

Filed Apr. 21, 1969, Ser. No. 16,831

Term of patent 14 years

Int. Cl. D24—02

U.S. Cl. D83—1

FIGURE 1 is a perspective view of a hemodialysis fluid conditioning and monitoring apparatus embodying my new design;

FIGURE 2 is a left side elevational view of the hemodialysis fluid conditioning and monitoring apparatus shown in FIGURE 1;

FIGURE 3 is a top plan view of the hemodialysis fluid conditioning and monitoring apparatus shown in FIGURE 1;

FIGURE 4 is a rear elevational view of the hemodialysis fluid conditioning and monitoring apparatus shown in FIGURE 1; and

FIGURE 5 is a front elevational view of the hemodialysis fluid conditioning and monitoring apparatus shown in FIGURE 1, with the front panel removed to reveal monitoring and control instrumentation.

I claim:

The ornamental design for a hemodialysis fluid conditioning and monitoring apparatus, as shown.
